UNITED STATES PATENT OFFICE.

CHARLES J. CARTER, OF KANSAS CITY, MISSOURI.

FLOORING.

Application filed February 28, 1927. Serial No. 171,422.

This invention relates to flooring and more particularly to the class of flooring manufactured in sections for shipment, assembly and installation on a floor.

5 Flooring of this character has been produced with floor blocks having vertically disposed fibres, a unit for shipment and installation consisting of a string or series of blocks with longitudinal side grooves cut 10 in the constituent blocks to receive splines that join adjacent units to produce a substantial floor. Horizontal transverse recesses are provided in selected blocks into which nails are inserted at the factory, the 15 points embedded in the wood, the nails to be driven to their calculated limit of travel to secure adjacent units together when units are installed. Flooring of this character is disclosed in my prior Patents No. 1,412,506, 20 April 22, 1922, and No. 1,507,813, September 9, 1924.

The object of this invention is to provide a unit capable of comprising a larger number of floor blocks than present practice 25 contemplates, which may offer advantages for shipping, installation and wear, and which would provide opportunity for supplying a commodity having a larger proportion of its laid area factory-prepared. In 30 accomplishing this object I also have effected other improvements in the art, which will be disclosed in the course of the description.

I offer as embodying my invention, a unit 35 or section of flooring composed of floor blocks dove-tailed together and provided with transverse grooves angularly disposed, nails inserted in the grooves and driven into the blocks to be driven to their limit upon installation of a unit in a floor to enter an 40 adjacent unit and so secure the two units together in the improved manner to be detailed.

These and other novel features of my invention will be more particularly described 45 with reference to the drawings in which:

Fig. 1 is a perspective view of a portion of a flooring installation constructed with units of my invention.

Fig. 2 is a horizontal sectional view of 50 the floor taken through the spline grooves.

Fig. 3 is a perspective view of a typical section or unit.

Fig. 4 is a perspective view of typical individual blocks of which the members of a unit are comprised. 55

Referring in detail to the drawings:

1 designates a tenoned block member of a unit of flooring, having a cross-grained top face 2 indicating the vertical direction of wood fibres in a block positioned for functioning, a side 3 having a substantially rectangularly horizontal groove 4 and the dovetail tenons or tongues 5 projected horizontally from the side 6. The end 7 of the block is smooth, and is designed and adapted for 60 close abutment to the opposite end of a similar block 1, a string or series of blocks 1 being juxtaposed for engagement by means of features mentioned as will be related, to a similar series of blocks 8. A block 8 has 65 the same general features as a block 1, that is, its fibres vertical, and it has the same sort of top face 9 and smooth end 10 as block 1, it is of the same size and shape as block 1, the difference being that a side 11 of block 8 70 is provided with dovetail mortises or grooves 12 adapted to receive the tenons of a block 1 by horizontal sliding engagement and alignment of two such blocks. The opposite side 13 of a block 8 is provided with a horizontal groove 14 similar to the groove in block 1, though oppositely disposed on the block. 75

Two types of blocks, 1 and 8, having been provided, a unit of my design is assembled 80 by projecting the tenons of a suitable number of blocks 1 into the mortises of a suitable number of blocks 8, in such order or arrangement as may be most convenient, to produce a desired section such as designated 85 15 on the drawings. The line or series of blocks of one type is offset from the other, so that the blocks are staggered, and a block 8 locks two blocks 1. Similarly the tenons of a block 1 being engaged with the grooved 90 portions of parts of two blocks 8, a block 1 locks two blocks 8, the interlocking co-operating to effect a substantial union of the two series of blocks. 95

I provide now, as an element of a unit 15, 100

and for its association with the other units in a flooring installation, the connector member 16 which is simply a nail driven at a peculiar and carefully calculated angle into a unit to hold two series of blocks more firmly together, and to provide a means for securing two units together. The position of a nail 16 in a unit is determined by the location of recesses 17 designed to receive the 5 nails, and provided in a predetermined number and proportion of blocks 8, produced horizontally and angularly extending into the block, and by such selective provision, spacing the nails 16 along the side of a unit 10 15 representing the sides 13, namely the grooved sides of the blocks 8.

The angular positioning of a nail is arranged for so that a maximum of efficiency for the engagement of the nail in the blocks 20 25 may be provided for. A nail, driven into the blocks on a horizontal diagonal, penetrates substantially the longest possible horizontal line from side to side of a block, and by emerging from a block 8 on a long diagonal perforation, obviously, because of the staggered construction, enters a block 1 in such a manner as to penetrate it also on a long diagonal. Such positioning of the 30 35 nails also causes them to avoid grooving penetration of a joint or the introduction of a nail point in such joint and between blocks.

A recess 17 is provided directed as a nail is to be directed when driven through adjacent blocks and units to connect units in a 35 40 laid flooring. Upon assembly of the blocks at the factory the two series or strings of blocks 1 and 8 are secured together by the dovetailing described and by the insertion of the nails in spaced selected blocks 8, and the driving of the nails, diagonally, into adjacent blocks 1 but not to the limit of travel of a nail nor to the opposite side 3 of a block 1. The result of such partial projection of the 45 50 nails to hold the parts of a unit is shown in Fig. 3, where it is observable that a nail is inserted through the groove 14 of a block 8, and that its head is sunk within the face of side 13 of the block.

An additional joining element is provided, 50 55 comprising a spline 18 seatable in the aligned grooves 4 of a string or series of blocks 1 of a unit 15, and co-operatively seatable in the aligned grooves 14 of a string of blocks 8 of another unit positioned adjacent the first named unit on a floor, as observable in Fig. 1, the splines being introduced into the grooves 14 after the nails have been driven home, and their heads removed from the said grooves.

Fig. 2 illustrates the manner in which the provision of nails as described permits of effective securing of units to units. A unit having been laid, and the nails it holds driven to their limit, a spline installed, and a second unit having been attached to the

first laid unit by the spline, a nail held by the second unit is driven to its limit, into the first laid unit and so secures the two units together. Since the units are provided as having offset strings of blocks, and the 7 blocks of one string are staggered with respect to the blocks of another string in the same unit, the diagonal penetration of the nails assures positioning in effective relations with the blocks.

I have illustrated and described my invention as exemplified in wooden floor blocks assembled into units of flooring, though the principles thereof may be used in connection with other forms and materials.

What I claim and desire to secure by Letters Patent is:

1. As an article of manufacture, a section of flooring comprising mated members dovetailed together and composed of blocks, the 8 blocks of one member staggered with reference to the blocks of the other member, and means for securing one section with another to form a floor.

2. As an article of manufacture, a unit comprising paired strings of blocks, the strings having grooves on their opposite faces, a spline to be received by opposed grooves of units assembled in a floor, and means for securing one unit to another.

3. As an article of manufacture, a section of flooring comprising mated members dovetailed together and composed of blocks, the blocks of one member staggered with reference to the blocks of the other member, the 11 members having longitudinal grooves in their opposite sides, and a spline seated in one of said grooves and adapted to be received by an opposite groove of another unit laid adjacent said unit on a floor.

4. As an article of manufacture, a unit of flooring comprising a plurality of members disposed side by side and composed each of a plurality of blocks, means for slidably engaging a block of one member with a block 11 of the other, grooves on opposite sides of engaged blocks, splines to be received by grooves of adjacent units on a floor, diagonal recesses in selected blocks, and nails inserted in the recesses and perforating the recessed 11 blocks and penetrating a block engaged thereby.

5. As an article of manufacture, a unit of flooring comprising mated members disposed side by side, a member composed of a plurality of blocks, dovetailing means of associating the members, a member having spaced recesses projected diagonally into the exterior side thereof, and nails inserted into the recesses axially thereof and perforating 12 the said member and penetrating the other member, the heads of the nails being spaced from the closure walls of the recesses.

6. In a fabricated floor, units comprising paired members composed of a plurality of

staggered blocks dovetailed together and having grooves in their opposite sides, selected blocks of one member having recesses projected on horizontal diagonal lines, and nails inserted through said recesses perforating said selected blocks and penetrating adjacent blocks of the other member, and

splines receivable by grooves of adjacent units, said recesses and nails being disposed so that the nails may be caused to perforate said penetrated blocks and penetrate diagonally blocks of adjacent units of a floor.

In testimony whereof I affix my signature.

CHARLES J. CARTER.
